MUSICAL INSTRUMENT

Floyd A. Firestone, Ann Arbor, Mich., assignor, by
mesne assignments, to Hammond Instrument
Company, Chicago, Ill., a corporation of Dela-
ware

Application September 6, 1938, Serial No. 228,477

16 Claims. (Cl. 175—363)

This invention relates to electrical musical instruments of the same general class as the invention disclosed and broadly claimed in United States Patent No. 1,953,753, granted to me on April 3, 1934.

In my aforesigned prior patent use is made of a multiplicity of capacitance reactance assemblies for producing alternating voltages at different tone frequencies. Said patent teaches how such assemblies can be used for the production of alternating voltages at harmonically related tone frequencies and substantially sinusoidal waveform, adapted selectively to be impressed upon the grid circuit of an electron tube amplifier and at controlled relative intensities to produce any desired complex waveform in the output circuit of said amplifier. Twelve similar reactances properly formed and driven in ratios of

1 to $\sqrt[12]{2}$

will produce alternating voltages at frequencies conforming to all fundamental tones of an even tempered musical scale and a predetermined number of harmonics of said fundamental tones.

In the embodiment of my invention now sought to be protected by Letters Patent, twelve identical capacitance reactances are employed, the forms, shapes and relationship of parts of each thereof being such as to insure production of larger and consequently more useful voltages than was possible heretofore.

An important feature of the invention is to provide a capacitance reactance embodying relatively rotatable undulatory instrumentalities in scanning relation to each other, the forms of which, aside from producing larger and more useful voltages will insure continuous production of substantially sinusoidal waveforms.

Another object is to provide an arrangement of identical capacitance reactances constituting a simple and exceedingly compact and light weight organization of voltage generators adapted readily to be accommodated in a small easily portable console.

A further important object of the invention is to provide means for shielding adjacent capacitance zones to prevent modulation of a tone by stray electrostatic flux induced at any zone not being drawn upon at the instant desired voltages are being conducted from others of the zones for the production of said tone.

Another object is to provide capacity reactances having rotatable instrumentalities serving as an inertia mass to counteract an otherwise ob-

jectionable effect of fluctuants occurring at the driving source or in the power transmission between said source and said scanning instrumentalities, thus to hold sensibly constant the necessary speeds of said instrumentalities and prevent changes in the pitch relation of the produced tones.

In the accompanying drawings:

Figure 1 is a schematic plan view of my improved system of capacitance reactances;

Figure 2 is a view in end elevation of the system shown in Figure 1;

Figure 3 is a vertical section through one of the multiple capacitance reactances shown in Figure 1;

Figure 4 is a schematic view in plan of a primary electrode and associated undulatory scanning instrumentality;

Figure 5 is a view in perspective of a primary electrode;

Figure 6 is a view in elevation of a scanning instrumentality common to a plurality of primary and secondary electrodes;

Figure 7 is a view in elevation of an assembly of primary and secondary electrodes;

Figure 8 is a schematic illustration of a slightly modified form of the invention in which two electrodes, each of undulatory form are in scanning relation to each other, and

Figure 9 illustrates a further modification of the invention.

The system of continuously varying capacitance reactances shown in Figure 1 of the accompanying drawings is broadly similar to the continuously varying reactance groups or assemblies 40 shown at Figure 3 in my aforesigned prior patent. In one form of the invention herein disclosed, each capacitance reactance includes a scanning instrumentality, preferably, but not necessarily in the form of a rotatable metallic disc 20, connected to earth and provided with suitably spaced apart concentric circles of scanning areas 21, the distance between the adjacent areas in any circle being an integral multiple of

any individual capacity area of an associated primary electrode, the form of which will be described presently. Eight circles of scanning areas are provided for each of said discs. The inner circle comprises 2 scanning areas, the next circle 4 such areas, the next 8 such areas; the next 16 such areas and so on to the outer circle of the series which has 256 of such areas. Thus, the grouping of the respective scanning areas is in the mathematical order of frequencies in octave relation. Assuming disc 20 in Figure 6 to

55

represent the disc "C" at the extreme left of Figure 1 of the drawings, it is apparent that it is a part of a multiple capacitance reactance adapted to produce alternating potentials at the tone frequencies of all "C" notes of a musical scale. Similarly, the next disc above disc "C" is a part of a multiple reactance for producing alternating potentials at tone frequencies of all "C" notes and so on to the last of the twelve discs which forms part of a reactance for producing potentials at frequencies for all the "B" notes. If as proposed herein, the ratio between any rotatable reactance and any other reactance above it is

1 to $\sqrt[12]{2}$

and if the numbers of scanning areas in the eight circles of the disc progress geometrically exactly in the same ratio, the tone frequencies of the generated potentials will be in equal temperament. While I show conventional belts and pulleys for transmitting these necessary incommensurate speeds to the respective discs 20 in Figure 1, it is understood that any well known means can be substituted therefor without departing from the spirit of my invention. These speeds can readily be approximated by the system of gears disclosed in the patent to E. G. Thomas, No. 1,156,329, dated Oct. 15, 1915.

Said discs 20 may each be approximately 5½ or 6 inches in diameter and about $\frac{1}{16}$ of an inch in peripheral width. In Figure 1 the twelve discs 20 are coaxially related to each other and each is fixed to its own driven shaft 22 having a pulley 23. At 24 is a drive shaft having pulleys 25, there being one thereof for each of the driven pulleys 23, the former connected to the latter by belts 26. The ratios of the diameters of adjacent pulleys 25 are

1 to $\sqrt[12]{2}$

The drive shaft 22 is belted or otherwise geared in some well known manner to a synchronous or other suitable constant speed motor 27.

Disposed at one side of each of the discs 20 is an electrode assembly 28. A detailed description of one of these assemblies will suffice for the entire series as they are all identical in every respect. Upon reference to Figures 3 and 7 of the drawings, 211 represents a mounting or support of non-conductive material. Extending from one side of said mounting are primary waveform electrodes 29 and secondary electrodes 30. Upon reference to Figure 7 it is noted that there are four groups of primary and secondary electrodes 29 and 30, there being one secondary for each pair of correlated primary electrodes in each of said groups. In this manner alternating voltages at different tone frequencies can be conducted to a work circuit from a common secondary electrode. Each secondary electrode comprises an arcuate continuous, smooth surfaced, brass plate, concentrically spaced apart from similar brass plates 31 to which the primary electrodes are firmly cemented in flatwise positions as shown in Figure 7 and insulated therefrom by thin strips of mica 332 or other well known insulating material.

In Figures 4 and 5 a form of primary electrode is shown for the continuous production of a substantially sinusoidal waveform in co-action with a correlated circle of scanning areas 21 on disc 20. In each of these figures, the primary electrode consists of a thin flat plate of conducting material having lateral, effective capacity areas 311, equi-distantly spaced apart from each other,

The scanning areas of disc 20 in Figure 4 are spaced from each other a distance about the center of shaft 22 equal to the angular distance between teeth of the coacting electrode 29.

- 5 I find in actual practice that to produce large voltages for all tone frequencies the number of effective capacity areas per primary electrode should progressively increase in the direction of the higher frequencies. This is so because of 10 the gradual diminishing surface proportions of the scanning areas in the direction of the outer high frequency circle in Figure 6. The low frequency primary electrodes, however, have each but a single capacity area. The electrodes for 15 the next two higher frequencies each have two such areas.

In Figure 3, the disc 20 is operatively associated with an electrode assembly so that during continuous rotation of said disc at its assigned speed, capacitance changes will occur between the respective primary and secondary electrodes with resulting production of alternating voltages in octave relation to each other, any one or more of which can be conducted to a work circuit to control a loud speaker. A network suitable for selective use of the voltages at different relative intensities is shown in my aforesaid prior patent. In said Figure 3 and as will also be appreciated on reference to Figure 7, it is noted that the outer two brass plates 31 of each group of primary and secondary electrodes serve to shield this capacitance zone of the device from the effects of shifting electrostatic flux generated at zones provided by others of said groups. 35 In this manner, a tone is sounded without being modulated by otherwise disturbing static effects occurring at electrodes from which no alternating voltage is being drawn at a particular instant.

- 40 Upon referring again to Figures 3, 6 and 7 and particularly on reference to Figure 3, it is noted that all primary and secondary electrodes of each of the aforesaid groups of electrodes are at a fixed radial distance apart from each other 45 and are also uniformly spaced radially from scanning portions in an associated circle of the disc. By reason thereof and due also to the manner of supporting the disc for rotary motion, the spacing of these parts is held effectively constant and unwanted tremolo effects avoided when sounding any tone.

From the construction herein set forth, it follows that when disc 20 is rotated, the primary electrodes will be periodically exposed to the secondary electrodes, the electrostatic capacity between them being always greater when a space is opposite them. The disc is grounded at 200. The brass plates 31 are each grounded, as shown 55 at Figure 3. Connection with a source of charging potential is made through input leads 300. All of the secondary electrodes connect with the input of an electron tube amplifying system 400, in the output circuit of which is an electrical 60 sound producer 500.

I stress the feature which consists in using grounded shields 31 between which is disposed a secondary electrode 30 serving two primary electrodes 29, thereby simplifying the construction and reducing capacity to ground by one half while yielding increasing voltage.

While I show discs 20, each constituting a scanning instrumentality common to a plurality of waveforms and adapted to originate voltages respectively conforming to notes in octave relation,

it is understood that this arrangement obviously can be modified without departing from the spirit of the invention. That is to say, the discs 20 can be formed so that each thereof will generate fundamental tone frequencies in octave relation and all frequencies that are harmonics of said fundamental tone frequencies. Such arrangement is provided for in my aforesaid prior Patent No. 1,953,753.

In Figure 8 a disc 100 is shown, the same being substantially like disc 20 in the first embodiment of my invention, and has concentric circles of capacity areas 125. Said disc is insulated from a driven shaft 750 on which it is fixedly mounted and is connected by conductor 775 to the input circuit 780 of an electron tube amplifier. The disc thus serves as a secondary electrode in coaction with an insulated, primary electrode 800, the latter connected to a direct current supply source 825. The primary electrode is the same as any electrode 29 in said first embodiment of my invention. In this form of my invention there, of course, will be one primary electrode for each circle of combined scanning and capacity areas on the disc 100.

In the form of my invention shown in Figure 3, the disc is of any material as it merely is employed as a scanning instrumentality. In the form shown in Figure 8, however, the disc functions in the dual capacity of an electrode means and scanning instrumentality and therefore is formed entirely of metal. The sets of circles of scanners may be milled in a circular piece of metal, the normal thickness of which is equal to the rim width. The individual equi-distantly spaced apart teeth or effective scanning areas of each circle are rectangular, providing straight sided lateral edges which are parallel to each other and right angularly relate to the solid side of the disc. The individual equi-distantly spaced teeth or forms of any primary electrode either in Figure 3 or Figure 8, are each substantially of the same shape and surface dimensions as any individual scanning area or tooth of an associated circle of scanning forms, and as they are spaced apart the same as said teeth or areas of said associated circle, it follows that the angular relation of the latter to the former is always the same at any moment during relative rotation of these parts. I find in practice that parts of the relative shapes herein shown produce periodic capacitance changes and alternating voltage of substantially sinusoidal waveform. I find also that by increasing the number of waveform teeth or areas on the primary electrodes in the direction of the higher frequencies, voltage of substantial strength is generated at each electrode. In other words, the dimensions are precalculated so that the combined capacity areas of any electrode is almost the same as the combined area or areas of any scanning form or forms coacting therewith at any instant, the respective parts being such that the space between adjacent scanning areas is equal to an integral multiple of the wavelength of the effective capacity area of a coacting electrode. The arrangement of scanning areas and electrodes in the instant embodiment of my invention is such that as a scanning form or solid area is leaving a coacting capacity area of an associated electrode, the next succeeding scanning form or solid area of the same circle of such forms or areas is in the active field thereof. The overall lengths of the primary electrodes shown in Figure 7 are en-

tirely effective when coacting with a like number of scanning forms in the associated circles on disc 20. They may, however, extend as far as desired about the axis of rotation of said disc 5 if larger voltage is desired.

I further find in practice that by covering the Bakelite support 211, Figure 3 with black conducting paint, except directly around the insulators 332, the latter being entirely concealed 10 behind the primary electrodes 29, extraneous noises, due to charges collecting on said insulators are reduced.

The voltage input leads 300 shown in Figure 3 will of course connect to a polarizing source in 15 a network which may be as shown in Figure 4 of my prior patent, the same including playing keys, each having multiple contacts connected in the network and with the voltage generators so that when a key corresponding to a selected 20 note is depressed, preselected generators will be drawn upon and the generated voltages impressed upon the input circuit of the amplifier 400. No claim is made herein for any particular means enabling the various voltages to be 25 utilized for the production of preselected tone timbres. Reference herein to my prior patent will be sufficient to enable persons skilled in the art to which the invention relates to carry same into practice as intended. It will suffice to say 30 that alternating voltage generators characterized as herein set forth can be used in any well known network having keying means and employing timbre determining stops.

While I show and have described rectangular 35 teeth on a rotary member the space between which is equal to the length of any coacting similar tooth of an associated primary electrode, early experiments disclosed that at the higher frequencies, an inductor having teeth, the space 40 between them being $2\frac{1}{2}$ times the width of the tooth itself, gave no harmonic as large as 1%, the reason being that the clearance between the electrode teeth and the teeth of the rotary member is an appreciable fraction of the distance between adjacent teeth on the inductor and the fringing of the lines of force around the teeth is such as to smooth out abrupt changes of capacity, yielding an approximately pure wave.

In Figure 9 of the drawings is disclosed a further modified form of combined scanning instrumentality and electrode means, the same comprising a magnesium disc having concentric undulating rings 50, each forming one wall of a groove 60 cut in one side of the disc. Coacting 55 with each set of undulations is an electrode 70, also of undulatory form. The electrode 70 may be connected to a polarizing source, and by means of a slip ring (not shown), the disc can be connected in the input circuit of an electron tube amplifier in the manner shown in Figure 8. Discs of the form shown in Figure 9 can be used advantageously for generating voltages of higher frequencies and can be used in combination with a disc of the kind shown in 60 Figure 3, formed to generate voltages of lower frequencies. The width of the groove at each of the rings of undulations 50 is sufficient to accommodate the electrode 70 and enable it to be disposed in concentric inductive relation to 65 said undulations.

What I claim as my invention is:

1. In an electrical musical instrument, a continuously variable condenser having a combined scanning instrumentality, an electrode providing a continuous succession of solid scanning and

capacity areas of one piece of conductive material; and a coacting electrode providing a similar succession of solid capacity areas, all of which are in a plane parallel to the path of movement of the scanning and capacity areas and are formed of one piece of conductive material.

2. In an electrical musical instrument, a continuously varying condenser comprising respective devices including electrodes forming one device and scanning means forming another device, said devices coacting to cause simultaneous capacitance changes at the electrodes at respective rates conforming to the vibrational frequencies of different musical tones; means for moving said devices relatively to cause the aforesaided capacitance changes; means for guarding each electrode from the effects of shifting flux fields generated at any other electrode; and means enabling selective conduction to a work circuit of one or more voltages produced in response to said capacitance changes.

3. In an electrical musical instrument, a continuously varying condenser comprising an electrode of undulating configuration; means for polarizing said electrode; and means coacting with said electrode to scan same at a rate to vary the capacitance of the generator according to a given tone frequency, the undulating configuration of the electrode presenting at one edge of the electrode capacity areas in side by side relation, the scanning means having effective straight sided scanning portions spaced apart from each other a distance equal to the wavelength of any capacity area of said electrode.

4. In an electrical musical instrument, a continuously varying condenser comprising a rotatable disc having concentric circles of scanning areas different in number from each other; a plurality of electrostatic shields; primary electrodes mounted flatwise against the respective shields; and electrically insulated therefrom; a secondary electrode common to said primary electrodes; and said shields being of lengths relative to their electrodes to protect one electrode from the effects of shifting electrostatic flux fields generated at any other electrode; and means for driving the disc at constant angular velocity to effect capacitance changes at the electrodes and simultaneous production of alternating voltages at different tone frequencies.

5. In an electrical musical instrument, a continuously varying condenser organization, a rotatable metallic member constituting a combined scanning instrumentality and secondary electrode adapted to impress alternating voltages at different tone frequencies upon the input circuit of an electron tube amplifier through a single electrical conductor, said member having a plurality of concentrically related sets of scanning forms; and a primary electrode for each set of said scanning forms inductively related thereto and adapted to be sequentially scanned thereby during rotation of the member relative thereto and thereby produce alternating voltage of predetermined tone frequency.

6. In an electrical musical instrument, relatively rotatable capacitatively related electrodes, one of which comprises a single piece of sheet metal formed with integrally connected and equidistantly spaced apart capacity areas providing a waveform pattern, the other electrode comprising a metallic member having a set of capacity areas, said areas of said set spaced apart from each other a distance equal to an integral multiple of any one of the first named capacity

areas; and means for moving the electrodes relatively to cause a scanning of the first named areas by said second named areas at a rate conforming to the vibrational frequency of a predetermined musical tone.

7. In an electrical musical instrument, a continuously varying condenser including a plurality of electrodes insulated from each other; a rotatable member having a plurality of concentrically related sets of scanning forms related to the respective electrodes simultaneously to scan same, each set of forms comprising a number of integral parts of said member adapted periodically to scan an associated electrode and cause capacitance changes at said electrode conforming to the vibrational periodicity of a predetermined musical tone; and means for mounting the electrodes to dispose same in operative coaction with the respective sets of scanning forms and providing electrostatic shielding to guard an electrode from the effects of shifting flux fields occurring at and in the proximity of any other electrode during operation of the generator.

8. An electrical musical instrument, a continuously varying condenser comprising a stator assembly having spaced apart primary electrodes; a mounting of insulating material for said electrodes; grounded metallic shields carried by the mounting or guarding an electrode from the effects of flux disturbances occurring at any other electrode during operation of the condenser; secondary grounded electrodes supported by said mounting and associated capacitatively with coacting primary electrodes; electrical conductors for conducting voltages from the secondary electrodes; and means by which the primary electrodes are periodically exposed to associated secondary electrodes at rates simultaneously to electrostatically originate alternating voltages at different tone frequencies.

9. A combined scanning instrumentality and electrode for variable condensers for producing alternating voltage of the frequency of a predetermined musical tone comprising a rotatable metallic disc grooved at one side in an axial direction and disposed concentric to the axis of rotation of the disc and having an undulating wall, said groove adapted to accommodate an electrode and enable same to be inductively related to said undulating wall.

10. In an electrical musical instrument an alternating voltage originating system comprising relatively movable organizations, one of which comprises concentric circles of spaced apart capacity areas, the other organization having means capacitatively related to said capacity areas, electrostatically to originate alternating voltages at different tone frequencies; means for polarizing one of said organizations; means enabling said alternating voltages to be impressed upon a work circuit, the capacity areas being shaped to cause each of the voltages to follow a substantially sinusoidal waveform; and means for guarding the capacity areas from the effects of shifting electrostatic flux originating any place in the system during relative motion of said organizations.

11. In an electrical musical instrument, a plurality of variable condensers having electrodes respectively provided with different numbers of capacity areas; means common to all of said condensers for simultaneously and continuously scanning the capacity areas of said electrodes periodically at relative rates to electrostatically develop alternating voltages at different tone fre-

quencies; and means for guarding each condenser from the effects of stray electrostatic flux originating at any other condenser.

12. In an electrical musical instrument, a continuously varying condenser comprising an electrode consisting of a disc wholly of conductive material; means for continuously driving said disc at an invariable velocity, said disc having a concentric circle of annularly spaced apart capacity areas; an electrode disposed relative to the disc electrode to be periodically scanned by capacity areas thereof; and a source of D. C. potential for oppositely charging said electrodes to thereby electrostatically originate alternating voltage of predetermined tone frequency during continuous relative rotation between them.

13. In an electrical musical instrument, concentrically related pairs of capacitatively related primary and secondary electrodes; a grounded metallic disc having at least one or more capacity areas for each pair of primary and secondary electrodes and disposed relative to said electrodes periodically to expose one thereof to the other during continuous rotation of said disc; a source of D. C. potential for oppositely charging the primary electrodes of each pair of said electrodes; and means for continuously driving said disc periodically to effect exposure of the secondary electrodes to the primary electrodes as aforesaid.

14. In an electrical musical instrument, a continuously varying condenser organization consisting of a secondary electrode having concentric circles of annularly spaced apart capacity areas, the number of such areas in any circle being different from the number in any other circle; a primary electrode for each circle of the aforementioned capacity areas and provided with one or more capacity areas, each having surface dimensions substantially the same as the surface dimensions of any individual capacity area in said circle; a source of D. C. potential for charging said primary and secondary electrodes; means mounting said electrodes to capacitatively relate their capacity areas to each other and enable continuous relative motion between said electrodes; and means for causing said continuous relative motion between said electrodes.

15. In mechanism of the class described, a continuously varying condenser organization including concentrically related pairs of primary and secondary electrodes, the primary and secondary electrodes of each pair of said electrodes being capacitatively related to each other and adapted to be oppositely charged from a source of D. C. potential; an electrostatic shield associated with the primary electrode of each pair; and a rotatable member driven at an assigned speed and having concentric circles of scanning areas, there being one such circle of scanning areas for each pair of electrodes and the number of said areas being predetermined and coacting with said electrodes periodically to expose one of said electrodes to the other and thereby electrostatically originate a waveform of alternating voltage of predetermined tone frequency; and means at each pair of primary and secondary electrodes providing a constant leak to ground for stray electrostatic charges generated during the aforementioned periodic exposure of the electrodes to each other.

16. In mechanism of the class described, a continuously varying condenser organization including concentrically related pairs of primary and secondary electrodes, the primary and secondary electrodes of each pair of said electrodes being capacitatively related to each other and adapted to be oppositely charged from a source of D. C. potential; an electrostatic shield associated with the primary electrode of each pair; and a rotatable metal disc constantly connected to ground and driven at an assigned, invariable speed and having concentric circles of scanning areas, there being one such circle of scanning areas for each pair of electrodes and the number of said areas being predetermined and coacting with said electrodes periodically to expose one electrode to another and thereby electrostatically originate a waveform of alternating voltage of predetermined tone frequency; and means at each pair of electrodes providing a constant leak to ground for stray electrostatic charges generated during the aforementioned periodic exposure of the electrodes to each other.

FLOYD A. FIRESTONE.
